(57) **CLAIM**

The ornamental design for a garage interior, as shown and described.

DESCRIPTION

FIG. 1 is a top perspective view of a first embodiment of a garage interior wherein a ceiling has been omitted for clarity;

FIG. 2 is a cross-sectional front perspective view thereof taken along line 2-2 from FIG. 1;

FIG. 3 is a cross-sectional rear perspective view thereof taken along line 3-3 from FIG. 1;

FIG. 4 is a cross-sectional right perspective view thereof taken along line 4-4 from FIG. 1;

FIG. 5 is a cross-sectional left perspective view thereof taken along line 5-5 from FIG. 1;

FIG. 6 is a top plan view thereof wherein the ceiling has been omitted for clarity;

FIG. 7 is a cross-sectional front elevation view thereof taken along line 7-7 from FIG. 6;

FIG. 8 is a cross-sectional rear elevation view thereof taken along line 8-8 from FIG. 6;

FIG. 9 is a cross-sectional right elevation view thereof taken along line 9-9 from FIG. 6;

FIG. 10 is a cross-sectional left elevation view thereof taken along line 10-10 from FIG. 6;

FIG. 11 is a top perspective view of a second embodiment of the garage interior wherein the ceiling has been omitted for clarity;

FIG. 12 is a cross-sectional front perspective view thereof taken along line 12-12 from FIG. 11;

FIG. 13 is a cross-sectional rear perspective view thereof taken along line 13-13 from FIG. 11;

FIG. 14 is a cross-sectional left perspective view thereof taken along line 14-14 from FIG. 11;

FIG. 15 is a cross-sectional right perspective view thereof taken along line 15-15 from FIG. 11;

FIG. 16 is a top plan view thereof wherein the ceiling has been omitted for clarity;

FIG. 17 is a cross-sectional front elevation view thereof taken along line 17-17 from FIG. 16;

FIG. 18 is a cross-sectional rear elevation view thereof taken along line 18-18 from FIG. 16;

FIG. 19 is a cross-sectional left elevation view thereof taken along line 19-19 from FIG. 16; and,

FIG. 20 is a cross-sectional right elevation view thereof taken along line 20-20 from FIG. 16.

(Continued)

The broken lines depict portions of the garage interior that form no part of the claimed design.

The dot-dash lines show boundary lines of the garage interior that form no part of the claimed design.
